UNITED STATES PATENT OFFICE

140,322

DESIGN FOR A COMBINATION PICTURE FRAME AND FLOWER-TUBE HOLDER OR SIMILAR ARTICLE

Judson Craig Eubank, New York, N. Y.

Application December 21, 1944, Serial No. 117,012

Term of patent 7 years

(Cl. D29—20)

To all whom it may concern:

Be it known that I, Judson Craig Eubank, a citizen of the United States, residing at New York, in the county of New York and State of New York, have invented a new, original, and ornamental Design for a Combination Picture Frame and Flower-Tube Holder or Similar Article, of which the following is a specification, reference being had to the accompanying drawing, forming part thereof.

Fig. 1 is a perspective view, showing my new design of a combination picture frame and flower-tube holder or similar article, and

Fig. 2 is a front elevational view thereof.

I claim:

The ornamental design for a combination picture frame and flower-tube holder or similar article, substantially as shown.

JUDSON CRAIG EUBANK.
